UNITED STATES PATENT OFFICE.

LESTER L. MORSE, OF SAN FRANCISCO, CALIFORNIA.

DISPLAY-RACK.

No. 918,186.

Specification of Letters Patent. Patented April 13, 1909.

Application filed August 19, 1908. Serial No. 449,321.

To all whom it may concern:

Be it known that I, LESTER L. MORSE, a citizen of the United States, residing in the city and county of San Francisco and State of California, have invented new and useful Improvements in Display-Racks, of which the following is a specification.

This invention relates to display-racks, and pertains especially to those for exhibiting tickets, post-cards, seed-envelopes, and the like. The use of a holder or display-rack for tickets, post-cards or seed-packets, and all other small articles which are usually artistically embellished, has become so general that it is necessary to produce a rack of extreme cheapness and simplicity, inasmuch as these racks are frequently distributed free to sales agents and stores by the manufacturer or wholesaler of the goods displayed. Again, it frequently happens that the articles displayed may vary in dimensions, in length or width, in which case it would be necessary to have a plurality of separate racks; but my invention comprehends the use of movable partitions to accommodate these variations.

The purpose of my invention is to devise a display-rack of such structure as will be cheap to manufacture, having the fewest different elements, which will have a main frame made principally of a single continuous sheet of metal, which will be extremely rigid, and which will be divided into various compartments or pockets with adjustable walls.

The invention consists of the parts and the construction and combination of parts as hereinafter more fully described and claimed, having reference to the accompanying drawings, in which—

Figure 1 is a perspective view, partly broken away. Fig. 2 is a plan of a wall element. Fig. 3 shows another form of wall element.

In the practical embodiment of the invention, I form the body of the rack from a single sheet of suitable material, preferably galvanized iron, bending this sheet, as shown in Fig. 1, to form a series of longitudinal troughs arranged in echelon, and having substantially vertical respective long and short, rear and front walls 2 and 3, and flat bottoms 4; the bottoms of the troughs being in different levels, and the entire device adapted to be supported at an incline by suitable means, as the bracket 6, so as to

maintain the bottoms 4 horizontal. The end of the sheet beyond the topmost rear wall 2 is folded over to provide a stirrup 7 to receive the pintles of the brackets 6, and the opposite end of the strip beyond the lowermost front wall 3 is bent down, as shown at 8, to provide a support for the lower end of the rack. The ends of the rack are faced by strips or plates 9, and the intermediate trough spaces are suitably divided off into pockets or compartments 10, either by means of the rigid partition plates 11 or the adjustable partition plates 12.

When the rack is to be used to display articles of standard and uniform dimensions, fixed partitions, such as 11, may be used. These partitions are conformable in shape to the cross-section of the compartment troughs, and the upper edge is cut in accordance with the pitch of the top of the walls.

When it is desired to display articles of various dimensions, movable partitions 12, Fig. 3, having oppositely projecting lugs 13 formed upon the vertical front and back edges may be used in lieu of the rigid partitions 11; the lugs 13 being designed to fit snugly against the front and rear walls and permit the partitions to be spaced at pleasure along the floor 4.

For the purpose of cleaning the compartments, the holes 14 may be provided in the bottoms of the pockets.

Having thus described my invention, what I claim and desire to secure by Letters Patent is—

1. A display-rack comprising a series of troughs arranged in echelon, with the bottoms and sides of the troughs made from a single sheet of material, said troughs having partitions to divide the same into pockets, said partitions being adjustable lengthwise in the troughs and means for supporting the rack at an incline.

2. A display-rack having a series of troughs formed by bending a continuous sheet of material, the bottoms of said troughs being in different levels and said troughs having longer rear walls and shorter front walls, end closures for the troughs, partitions in said troughs forming pockets, and a foldable bracket hinged to the top of the rack, the end of the sheet beyond the topmost rear wall being folded over to provide a bearing, and the bracket being provided with pintles to engage said bearing,

said bracket adapted to fold relative to the rack so as to maintain the bottoms thereof substantially horizontal.

3. A display-rack having a series of 5 troughs formed by bending a continuous sheet of material, the bottoms of said troughs being in different levels and said troughs having longer rear walls and shorter front walls, end closures for the troughs, 10 partitions in said troughs forming pockets,

and a foldable bracket hinged to the top of the rack, said partitions being adjustable lengthwise in the troughs.

In testimony whereof I have hereunto set my hand in presence of two subscribing witnesses. 15

LESTER L. MORSE.
